E. E. SPRINKLE

ACETYLENE GAS GENERATOR

Filed Sept. 2, 1922

Patented Mar. 11, 1924.

UNITED STATES PATENT OFFICE.

EDGAR E. SPRINKLE, OF FORT SMITH, ARKANSAS.

ACETYLENE-GAS GENERATOR.

Application filed September 2, 1922. Serial No. 585,964.

To all whom it may concern:

Be it known that I, EDGAR E. SPRINKLE, a citizen of the United States, residing at Fort Smith, in the county of Sebastian and State of Arkansas, have invented certain new and useful Improvements in Acetylene-Gas Generators, of which the following is a specification.

This invention relates to acetylene gas generators and has for its object the provision of an inexpensive and efficient device by the use of which dry gas will be delivered to the point of use and in which the feeding of the carbide will be automatically and effectually controlled and the access of water to the carbide-controlling valve and the part by which it is actuated will be prevented. Other objects of the invention will appear incidentally in the course of the following description, and the invention resides in certain novel features which will be particularly pointed out in the claims following the description.

In the drawings—

Figure 1 is a vertical section of an acetylene gas generator embodying my improvements;

Fig. 2 is a detail section illustrating a drain cock.

In carrying out my invention, I employ a reservoir which is constructed with an inner wall 1 and an outer wall 2, these walls being preferably cylindrical and concentric and united with an imperforate bottom 3 by welding or otherwise so as to be free of open joints. The bottom of the container over the area defined by the inner wall may be reinforced and constructed to carry a filling 4 of sawdust or other material which will prevent the transmission of extremely low temperatures through the bottom of the generator to the water therein so that freezing of the water will be avoided. The filler 4 is contained between the bottom 3 and an inner false bottom 5 which may be secured to the bottom 3 by rivets or other devices, indicated at 6, so as to securely hold the filler, as will be readily understood. Disposed centrally within the container or generating chamber defined by the inner wall 1 is a tube 7 which extends to the top of the said chamber and is braced at its upper end by bars 8 extending between the tube and the wall 1 and has its lower end resting upon the bottom of the generator and welded or otherwise connected there-

with so that no open joints will be permitted. The space between the inner and outer walls of the generator is partly filled with oil or other liquid, indicated at 9, and receives the lower end of a bell 10, the liquid forming a seal for the open lower end of the bell in a well-known manner. The upper end of the bell is closed by a cap or cover 11 and at the center thereof a neck 12 rises to support a hopper or carbide container 13. The bottom 14 of this hopper inclines downwardly toward the center thereof and has an opening 15 therethrough to permit the passage of the carbide. To the under side of the hopper around this opening 15, I secure a disk or collar 16 which forms a seat for the valve 17 and has a central opening 18 therethrough, the edge of said opening being slightly turned downwardly, as shown, whereby to facilitate the flow of the carbide into the bell. Above the bottom 14, the hopper is preferably cylindrical and its upper end is covered by a cap or hood 19 having a central filling opening 20 which is normally closed by a cap or plug 21. Extending diametrically across the hopper above the valve 17 is a bridge or deflector 22 which is of a flared or inverted V-shaped cross section so that the carbide will be deflected toward the sides of the hopper and may flow down the tapered or inclined bottom 14 of the same without passing directly onto the valve 17 and accumulating thereon so as to choke its operation. The valve 17 is preferably of the conical form illustrated so that it may readily pass relatively upward through the carbide, but it may be of any other form if desired. The base of the valve is of sufficient diameter to extend entirely over the escape opening 18 and prevent the passage of carbide through the same when the valve is seated. A long stem 23 depends from the valve 17 and has its lower end disposed within the tube 7 so that it may, in the operation of the device, impinge against the bottom of the generator, as will be presently particularly set forth. The tube 7 obviously will prevent contact of the water with the valve stem, and possible freezing of the water consequently will not interfere with the operation of the bell nor prevent the free movement of the stem. Above the upper end of the tube 7, a deflecting cap 24 is carried by the stem and this cap is of greater diameter than the said tube so that it will

turn the carbide aside and prevent the same entering the tube, and when the bell is in its low position the cap will rest on the end of the tube and effectually cover the same.

5 The generating chamber is supplied with water through a filling pipe 25 which is preferably arranged vertically at the exterior of the generator, as shown, and has its lower end coupled to a horizontal pipe 10 27, one end of which enters the generating chamber and the other end of which projects laterally beyond the filling pipe, as shown at 28. The outer end of this pipe 28 is normally closed by a plug or cap 29 15 which may be readily removed when draining of the generating chamber is desired. The removal of the carbide dregs is thus facilitated. To withdraw the liquid in the space between the inner and outer walls of 20 the generator, I provide a drain cock 30 which is fitted into the outer wall in any convenient manner and establishes communication with the liquid sealing space, it being readily understood that the pipe 27 is 25 closed to said space and is open only to the generating chamber.

Within the upper portion of the generating chamber, I provide a drier or filter 31 which consists of a shell having one end 30 perforated or formed of a foraminous material of any preferred form, indicated at 32, while its opposite end is closed except for the connection therewith of the upper end of a gas pipe 33. The shell is filled 35 with cotton or other material, indicated at 34, which will permit a ready flow of gas but which will absorb and remove therefrom any moisture which may be carried thereby and which would otherwise pass 40 into the gas pipe 33 and thence into the circulating system. The gas pipe 33 extends down to the bottom of the generating chamber and then passes laterally outward through the same, as shown at 35, so as to 45 be coupled to the pipe 36 which leads to the point or points of use. The pipe 35 is provided with an extension 37 which is normally closed by a plug or cap 38 and which facilitates drainage or cleaning when 50 necessary.

Upon the exterior of the generator at the upper end of the same, I pivotally attach props 39 which may be of any preferred form and dimensions and are adapted to 55 engage under the overhanging bead or flange 40 on the bell so that the bell may be supported in a raised position when cleaning of the apparatus is desired. Obviously, unless the bell were thus readily supported in its raised position, the filling of carbide might occur when the apparatus 60 contains no water or while workmen may be engaged in repairing or cleaning the same and this action would not only involve 65 a waste of carbide but would be very apt to

lead to damaging explosions. In the cap or cover 11 of the bell, I provide a vent 41 which is normally closed by a cap or plug 42 but which may be opened so as to break the vacuum in the upper end of the bell 70 or permit escape of surplus gas when, for any reason, access to the interior of the bell may be desired.

Upon the bridge or deflector 22, I provide a supplemental hopper 43, the lower 75 end of which registers with an opening 44 through the deflector. A conical valve 45 is provided within the supplemental hopper and normally seats upon the bottom thereof, under the weight of the contained carbide, 80 to close the opening 44. The stem 46 of this valve depends through and below the deflector and is equipped with a bumper 47 axially aligned with the valve 17 but normally spaced from the same. In the normal 85 operation of the apparatus, the valve 17 remains out of contact with the bumper 47 and the carbide in the supplemental hopper constitutes a reserve or emergency supply. When the main supply of carbide is exhausted, the pressure in the bell will be so reduced that the bell may descend to the full limit of its movement thereby bringing the bumper 47 against the valve 17 and effecting unseating of the valve 45. The reserve supply of carbide will then flow into the bell and sufficient gas will be generated to maintain combustion at the burners until a fresh stock of carbide may be obtained. When the pressure of the gas is so reduced 90 as to bring the reserve supply of carbide into use, the lessening of the flame at the point of use will notify the user of the condition so that he may at once replenish the supply. 95

The operation of the apparatus will, it is thought, be readily understood. Water is supplied to the generating chamber through the filling tube 25 and the lateral pipe 27 and carbide is stored in the hopper 13. When 100 there is no gas in the bell, the weight of the bell will carry it downward and the valve 17 will, of course, drop with the bell until the lower end of its stem 23 impinges upon the bottom of the generator, whereupon the 105 continued downward movement of the bell will effect unseating of the valve and carbide will then at once flow through the opening 18 into the generating chamber. The mingling of the carbide with the water will at once 110 generate the gas which will tend to accumulate in the top of the bell and find its only outlet through the drier or filter 31 which establishes direct communication with the 115 pipes of the circulating system. The flow 120 through the circulating system is, of course, controlled by valves at the several points of use and by a master valve interposed at any point and indicated at 33. As the gas is 125 generated and accumulates in the upper por- 130

tion of the bell, the pressure exerted by it upon the top or cover 11 of the bell will raise the latter until the valve seat 16 engages the valve 17, whereupon the further flow of carbide will be cut-off in an obvious manner. As the gas continues to accumulate, the bell will continue to rise and the valve will remain seated, but its stem will be lifted from the bottom of the generator so that the parts will assume the relative positions shown in the drawing. As the gas is used, the pressure exerted by the diminishing volume of gas will, of course, decrease and the bell will then eventually descend so that the described operation will be repeated and a fresh supply of carbide permitted to flow to the water in the generating chamber. The operation will continue automatically until the entire supply of carbide has been exhausted and the only attention upon the part of the user will be that needed to maintain a sufficient supply of carbide in the hopper. My apparatus is exceedingly simple in the construction and arrangement of its parts and may be set up for use at a very low cost and, when set up and in use, will furnish a plentiful supply of dry gas to the burners.

Having thus described the invention, what is claimed as new is:

- 30 1. The combination of a generating chamber having a central tube fixed to and rising from its bottom to its top and provided with an open upper end, a bell fitted over the generating chamber and sealed against the same, a hopper carried by said bell and having an outlet opening in its bottom, a valve controlling the flow through said opening, and a stem depending from said valve within the central tube of the generating chamber and adapted to impinge upon the bottom of said chamber whereby to effect unseating of the valve and permit the feed of carbide.
- 45 2. The combination of a generating chamber, a bell fitted over the generating chamber and sealed against the same, a tube rising centrally from the bottom of the generating

chamber to the top thereof and having an open upper end, a hopper on the bell having an outlet opening in its bottom, a valve normally closing said opening, a stem depending from said valve into the said tube and adapted to impinge against the bottom of the generator, and a deflecting guard carried by said stem below the valve and adapted to cover the upper end of said tube.

3. The combination of a generating chamber, a bell fitted over said chamber and sealed against the same, a hopper carried by said bell and having an opening in its bottom to establish communication with the bell, a valve normally closing the opening in the bottom of the hopper, a stem depending from said valve and adapted to impinge against the bottom of the generating chamber whereby descent of the bell will unseat the valve and ascent of the bell will permit the valve to seat, a supplemental hopper within the first mentioned hopper, a valve normally preventing discharge from the supplemental hopper and arranged in vertical alinement with the first-mentioned valve, and means whereby said second-mentioned valve will be opened by contact with the first-mentioned valve in an extreme low position of the bell.

4. The combination of a generating chamber, a bell fitted over said chamber and sealed against the same, a hopper carried by said bell and having an opening in its bottom to establish communication with the bell, a valve normally closing the opening in the bottom of the hopper, means whereby descent of the bell will unseat the valve and ascent of the bell will permit the valve to seat, a supplemental hopper within the first-mentioned hopper, a valve normally preventing discharge from said supplemental hopper, a stem depending from second-mentioned valve, and a bumper on the lower end of said stem arranged to be lifted by the first-mentioned valve to open the second-mentioned valve in an extreme low position of the bell.

In testimony whereof I affix my signature.

EDGAR E. SPRINKLE. [L.S.]
